[57] CLAIM

The ornamental design for a chair, as shown and de-
scribed.

DESCRIPTION

FIG. 1 is a perspective view of a chair showing my new
design;

FIG. 2 is a front elevation thereof;

FIG. 3 is a top plan view thereof;

FIG. 4 is a left side view thereof, the opposite side being
a mirror image of the side shown; and,
FIG. 5 is a rear elevational view thereof.
